Honeywell Inc., Minneapolis, Minn., a corporation of Delaware

Filed Dec. 6, 1965, Ser. No. 66

Term of patent 14 years

(Cl. D2—3)

The dominant features of my design reside in the portion shown in full lines.

I claim:

The ornamental design for a liquid dispenser, substantially as shown and described.
